UNITED STATES PATENT OFFICE.

HENRY D. JUSTI, OF PHILADELPHIA, PENNSYLVANIA.

ARTIFICIAL TOOTH-CROWN.

SPECIFICATION forming part of Letters Patent No. 644,803, dated March 6, 1900.

Application filed October 6, 1899. Serial No. 732,764. (No model.)

To all whom it may concern:

Be it known that I, HENRY D. JUSTI, a citizen of the United States, residing in the city and county of Philadelphia, State of Pennsylvania, have invented a new and useful Improvement in Fastenings for Artificial Tooth-Crowns, which improvement is fully set forth in the following specification and accompanying drawings.

My invention has for its object the convenient, firm, and reliable connection of an artificial tooth-crown with a natural root; and it consists of a pin (divided or open-sided) or anchor and a crown of novel construction, whereby they may be effectively secured to each other while the anchor permits access to the root when the crown is removed without removing said anchor from its seat in said root.

Figure 1 represents a perspective view of a fastening for an artificial tooth-crown embodying my invention, the parts being separated. Fig. 2 represents a vertical section thereof on line $x-x$, Fig. 4, the parts being connected. Fig. 3 represents a top or plan view of the crown. Fig. 4 represents a horizontal section on line $y-y$, Fig. 2. Fig. 5 represents a perspective view of another form of my invention. Fig. 6 represents a perspective view of another part of the invention, and Fig. 7 represents an end view thereof.

Similar letters of reference indicate corresponding parts in the figures.

Referring to the drawings, A designates an artificial tooth-crown, and B designates a vertical cavity therein. On one of the walls of said cavity is the vertically-extending tongue C, which projects inwardly from said wall into said cavity, so as to partially occupy said cavity and is of U or V shape in cross-section.

D designates a pin or anchor, which consists of a piece of suitable metal bent or otherwise produced in channeled or bifurcated form with an open or divided side and having the longitudinally-extending canal E therein, the upper end of said anchor being adapted to enter a natural root and the lower end to enter the cavity B of the crown A, it being noticed that the canal E receives the tongue C, the walls of the divided or open side of the pin engaging said tongue, whereby the anchor is interlocked with the crown through the medium of said tongue, it being further

noticed that when cement or filling material is introduced into the cavity B the anchor is firmly and reliably connected with the crown 55 and the latter may be similarly secured to the root.

Owing to the projection of the tongue into the canal E, the latter is prevented from closing or contracting, and thus loosening of the 60 anchor in the crown is prevented, it being furthermore seen that when the anchor is secured to the root the exposed portion or outer end of the anchor may have the crown readily fitted to the same in a convenient manner, 65 as the tongue and canal act as a guide for properly fitting the crown in said end with the advantages of connecting said parts, as has been stated.

Should it be desired to have access to the 70 root, the crown may be displaced and the filling in the anchor or pin removed, when the canal of the anchor or pin admits of the passage of the point of a desired instrument through the same to the root or nerve thereof. 75

In Fig. 5 the sides of the anchor or pin are corrugated or roughened, as at F, to increase the holding action of the cement or filling thereon, said pin being V-shaped, while in the other figures it is U-shaped; but to these features I do not limit myself. 80

When desired, I insert in the canal or groove E a core, such as G, the same being cemented in said canal, so that in case of a required operation on the root the crown will 85 be removed, when access is had to the core, the latter then being withdrawn, leaving the canal free for the introduction of an instrument to reach the root.

It is evident that the anchor or pin may be 90 fused in the crown, thus firmly connecting the same, the other advantages stated being preserved.

Having thus described my invention, what I claim as new, and desire to secure by Letters 95 Patent, is—

1. An anchor or pin for connecting an artificial tooth-crown with a natural root consisting of a piece of material having its ends adapted to enter said crown and root and 100 formed with a longitudinally-extending canal and a vertically-extending open side.

2. An artificial tooth-crown having a cavity therein, and a member on a wall of said

cavity integral therewith and partially occupying said cavity and an anchor having its ends adapted to enter respectively said crown and a natural root, and provided with a vertical canal adapted to receive said member and a divided side, the walls of which latter are adapted to engage said member.

5 3. An anchor with a longitudinally-extend-

ing canal or groove therein for the purpose set forth, and a core removably occupying 10 said canal.

HENRY D. JUSTI.
